WILLIAM H. ROGERS, OF HARLEN, ILLINOIS.

Letters Patent No. 73,049, dated January 7, 1868.

IMPROVEMENT IN GATES.

The Schedule referred to in these Letters Patent and making part of the same.

TO ALL WHOM IT MAY CONCERN:

Be it known that I, WILLIAM H. ROGERS, of Harlen, in the county of Winnebago, and State of Illinois, have invented a new and improved Gate; and I do hereby declare the following is a full and exact description of the same, reference being had to the accompanying drawings, and to the letters of reference marked thereon.

Figure 1 is a side elevation of my invention.

Figure 2 is a rear elevation, showing the gate opened.

Figure 3 is a detached plan view of the rollers at the bottom of the apparatus.

Figure 4 is a detached view of the post A', showing the longitudinal groove therein, and

Figure 5 is a detached side elevation of the latch-apparatus.

This invention consists of a gate provided with such mechanism that it may be operated from a carriage without necessitating the dismounting of the occupant therefrom, as will be hereinafter fully described.

To enable others to make and use my invention, I will now proceed to describe its construction and operation.

A represents the main post of the gate set vertically in the ground or on a sill. To the upper end of the post is hinged the upper rail, *a*, of the gate, which rail projects in rear of the post *A*, passing between the two upright posts *b* *b'*, and projecting also in rear of them to a suitable distance, and being provided with a weight, *c*, of sufficient gravity to nearly counterpoise the gate. The other rails, *a'*, of the gate are connected with the upper rail and with each other by the cross-pieces *d* *d'*, on the lazy-tongs principle, the rails closing together as the gate swings upward, and expanding as it comes downward, in the well-known convenient manner. At the opposite end of the gate is the post *A'*, similar to *A*, both being provided with longitudinal grooves, *a''*, on their inner sides, in which are the ends of the gate-rails when closed, and by means of which the gate is stayed against lateral pressure. To the counterpoise *c*, at points in rear of the centre, are attached the ends of two cords, *e* *e'*, one of which passes over the sheave *h*, in the post *b*, and runs thence to the sheave *i*, mounted on the top of the T-post *k*. The other cord, *e'*, in like manner passes over the similar sheaves *h' i'*, mounted on the similar posts *b' k'*, on the opposite side of the gate. The posts *b* *b'* are placed only far enough apart to admit of the free working of the counterpoise between them. The T-posts *k* *k'* are to be set in the ground opposite the main post *A*, and far enough therefrom, and low enough to enable the occupant of a carriage approaching the gate to grasp the handles *l* *l'* *m* *m'* of the cords *e* *e'* *n* *n'* without dismounting. Just above the counterpoise *c*, a horizontal bar, *o*, is attached at each end to one of the posts *b* *b'*. On the upper side of this counterpoise is arranged a latch consisting of a small bar, *o'*, sliding in supports *r* *r'*, between which is a spiral spring, *s*, around the bar *o'*. The forward end of the bar *o'* forms a catch which impinges on the cross-bar *o*, and frustrates the intent whenever the gate is attempted to be lifted up without employing the cords. To the rear end of the bar *o'* are attached the ends of cords *n* *n'*, which pass through the eye *t* on the counterpoise, and thence to the rollers *u* *u'*, mounted in suitable frames at the lower ends of the posts *b* *b'*. The cord *n* passes under the roller *u*, thence up over the sheave *v*, near the upper end of the post *b*, whence it runs to the sheave *w*, on the top of the T-post *k*, where it is attached to the handle *m*. The other cord, *m'*, in like manner passes under the roller *u'*, and over the similar sheaves, *v' w'*, in the posts *b' k'*, and is attached to the like handle, *m'*. The cords *e* *n* *e'* *n'* are provided with hanging weights *x* *y* *x'* *y'*, between the sheaves *h i h' i' v w v' w'*, respectively, for the purpose of taking up the slack.

The operation of my invention is as follows: Suppose a carriage approaches the gate on the side of the T-post *k*. The occupant pulls the handle *m* of the cord *n*, the opposite end of which is attached to the rear end of the latch-bar *o'*. By the force of the pull the latch-bar is drawn clear of the cross-bar *o*, the counterpoise *c* drawn downward, and the gate raised. The carriage having passed through, the occupant then pulls the handle *l'* of the cord *e'*, the opposite end of which is attached to the upper side of the counterpoise at a point, as has been said, in rear of the centre. Consequently the counterpoise is raised by the force of the pull, and the gate again lowered into its place, whereupon the latch-bar *o'* immediately catches again on the cross-bar *o*. The same operation is, of course, gone through with, whichever side of the gate is approached. As the operator is always nearer the gate when it is to be closed than when it is to be opened, (being separated from it in the one case by the length of the horse and part of the carriage, and in the other case only by part of the carriage,) the handles by means of which the former operation is performed are placed at the ends of the T-posts next the gate.

Having thus fully described my invention, what I claim as new, and desire to secure by Letters Patent, is—

1. The combination of the gate *a* *a'* with the cord *n* and the roller *u*, sheaves *v* *w*, and handle *m*, or an equivalent, arranged for the purpose of opening the gate substantially as described.
2. The combination of said gate with the cord *e* and the sheaves *h* *i* and handle *l*, or an equivalent, for closing the gate substantially as described.

WILLIAM H. ROGERS.
